W. D. NELSON,

DRUM.

APPLICATION FILED OCT 6, 1919.

1,391,786.

Patented Sept. 27, 1921.

UNITED STATES PATENT OFFICE.

WESLEY D. NELSON, OF CHICAGO, ILLINOIS.

DRUM.

Specification of Letters Patent. Patented Sept. 27, 1921.

1,391,786.

Application filed October 6, 1919. Serial No. 328,803.

To all whom it may concern:

Be it known that I, WESLEY D. NELSON, a citizen of the United States, and a resident of Chicago, county of Cook, and State of Illinois, have invented certain new and useful Improvements in Drums, of which the following is a specification.

My invention relates generally, to improvements in drums no matter what the type may be, whether, base, snare, tympanic, or otherwise, but relates more particularly to means for tensioning the heads thereof.

The usual form of drum is formed of a hollow cylinder over each end of which is tightly stretched a piece of skin or vellum. Some drums are not cylindrical in form and have only a single skin. In every form, however, the skin or vellum must be very tightly stretched in order that the sound when beaten will be correct.

It is important for a number of reasons that the tension of the skin should be maintained at a predetermined tension for unless this be done the sound emanating from the drum when beaten will vary and thus detrimentally affect the performance of the drummer, particularly when the instrument is being played in an orchestra.

Again, uniformity of tension is desirable for the reason that if too strong a tension be applied, the skin will break and in fact in drums heretofore devised this is quite a common occurrence. With constructions, heretofore used, the tuning of a drum and the maintenance of that tone quality is difficult, if not impossible, of attainment. For example, if the drum be tensioned in a room or locality having a given temperature or different climatic condition, the tension on the skin or vellum, will be found to vary to such an extent that the tonal quality of the same drum will be different, indeed. If the temperature and climatic change be violent enough the skin will be destroyed.

It is an object of my invention to provide a drum construction in which it shall be possible to secure and maintain a desired tonal quality even though the drum be subjected to temperature and climatic changes.

Again it is an object of my invention to provide a drum construction in which breakage of the skin shall be very greatly minimized, if not entirely eliminated.

It is also an object of my invention to provide a drum construction which shall actually serve notice upon the user in the event

of a dangerous tension being placed upon the drum skin so that the tension may be readily corrected not only to restore tonal quality but to prevent destruction of the skin.

I aim also to provide a drum construction or attachment which may be utilized in conjunction with the drum body, heads, and other parts of drum constructions which have proven best adapted for the particular service required.

My invention consists generally in the form, arrangement, construction, and coaction of the parts whereby the above named objects, together with others that will appear hereinafter, are attainable, and my invention will be more readily understood by reference to the accompanying drawings which illustrate what I consider, at the present time, to be the best embodiment thereof.

In said drawings:

Figure 1, is an elevation of a drum embodying my invention, one of the parts being shown in section better to disclose the interior construction thereof.

Fig. 2, is a fragmentary view upon an enlarged scale of one of the tensioning members or devices.

Fig. 3, is a detailed view illustrating the tension indicating feature; and

Fig. 4, is a view of one of the members of the tension indicator, separate and apart from the other parts.

Fig. 5 is a sectional view of the body of the drum 1 and the hoops 4 and 5 showing the tensioning device in position and indicating how the device acts upon the skins.

In Fig. 1, of the drawings, 1, represents the body of the drum which it will be understood, is a hollow cylinder and which may be of metal, wood or composite materials, in accordance with approved or desired practice. This is a drum construction which is much used and which is provided with a skin 2, at one end and a skin 3, at the other end, which are stretched over the ends of the cylinder by means of the hoops or bands 4 and 5, respectively. When the hoops 4 and 5, are moved toward the center of the drum, i. e. longitudinally inward, the skins 2 and 3 are subjected to a greater tension and when the hoops 4 and 5 are moved in the opposite direction the tension is relieved or in other words, the skin is less taut. Of course, the action of a single skin and the single hoop or band may be considered as a sufficient

illustration for the skin at the other end is a mere duplication thereof, except that in practice one end of the drum is usually used as a snare head when the drum is of the construction shown. I have provided a number of tensioning devices 6 which are equally spaced around the circumference of the drum and which may vary in number and spacing, depending upon variations in the size of the drum. Each of these tensioning devices is alike in construction and operation, and for this reason a description of the construction and operation of one will serve for all.

15 The tension device comprises in the present instance, a tubular member 7 which is secured to the outer surface of the drum 1 as by means of straps 8. The ends of the member 7 are threaded as indicated at 9 and 10, for co-action with the cap members 11 and 12. The caps 11 and 12 are provided with central openings 13 and 14, respectively, in which are slidably mounted cylindrical members 15 and 16, respectively, and which have portions 17 and 18, respectively, which extend a considerable distance into the tubular member 7. At the inner ends of the members 17 and 18 will be found washers 19 and 20, respectively, which are secured in place by means of the nuts 21 and 22, and between the washers and the inner faces 23 and 24, respectively, of the cap members 11 and 12, are interposed coil springs 25 and 26, respectively. Rods 27 and 28 are screwed into the members 15 and 16 and the other ends of the rods 27 and 28 engage devices 29 and 30, which embrace the hoops 4 and 5 whereby the tension of the skins 2 and 3 can be altered as before described. Obviously the tension springs 25 and 26 tend to move the hoops or bands 4 and 5 toward each other and thereby place the skins under a predetermined tension depending upon the size and character of the springs. The tension of the springs 25 and 26 may be changed by turning the rods 27 and 28. If they are turned in one direction they will be screwed into the members 15 and 16 and if they are turned in the opposite direction they will be screwed outwardly, in the one instance shortening the distance and placing the drum skins under greater tension and in the other instance lengthening the distance and reducing the tension. On the face of the members 15 and 16 are impressed letters D and T as is best shown in Figs. 3 and 4 and for the purpose of disclosing these symbols the caps are cut away as indicated at 31. When the skin is under proper tension the letter T shows through the opening 31 with the arrows 32 in line with the outer end of the cap. Should climatic changes, or temperature conditions change so that the skin would be placed un-

der a very great tension the member 15 or 65 16, as the case may be, would move outwardly compressing the spring and bringing the letter D into view, which would indicate to the drummer that the heads or skins had reached a dangerous tension such as would likely cause breakage unless immediately corrected. In such an event the tension can be very quickly restored to normal by simply turning the rods 27 and 28 to slightly lengthen them. The spring construction, of course, yields to a considerable extent and is very helpful in preventing breakage of the skins. The drummer can very readily adjust the tension to desired magnitude thus securing the proper tonal quality as the tension is always properly indicated.

Inasmuch as this disclosure will suggest to others skilled in the art to which this appertains, certain modifications whereby the substantial objects and purposes of my invention may be attained I do not wish to be limited to the specific construction herein shown and described, except as may be necessary by limitation in the hereunto appended claims.

I claim:

1. A drum, a skin therefor, a hoop for placing said skin under tension and means for drawing said hoop, said drawing means including a device fastened to the drum, a 95 rod slidable in said device, a spring interposed between said device and the end of said rod, means at the other end of the rod for engaging said hoop, and symbols on said 100 slidable rod to indicate the degree of tension.

2. A drum, a skin therefor, a hoop for placing said skin under tension and means for drawing said hoop, said drawing means including a device fastened to the drum, a 105 rod slidable in said device, a spring interposed between said device and the end of said rod, means at the other end of the rod for engaging said hoop, and symbols on said 110 slidable rod to indicate the degree of tension, said rod being composed of sections and screw means for adjusting same.

3. A drum, a skin therefor, a hoop for placing said skin under tension and means for drawing said hoop, said drawing means 115 including a device fastened to the drum, a rod slidable in said device, a spring positioned to tend to move the rod axially of the drum, means for engaging said hoop whereby any movement of the rod results 120 in corresponding movement of the hoop, and means for disclosing the degree of tension of the skin whereby it is possible to place the skin under desired predetermined tension.

In testimony whereof, I have hereunto set 125 my hand, this 12th day of September, 1919.

WESLEY D. NELSON.
